UNITED STATES PATENT OFFICE.

THORSTEN VON ZWEIGBERGK, OF PRESTON, ENGLAND.

MOTOR-STARTING SWITCH.

No. 836,427.

Specification of Letters Patent.

Patented Nov. 20, 1906.

Application filed May 21, 1906. Serial No. 817,868.

To all whom it may concern:

Be it known that I, THORSTEN VON ZWEIGBERGK, a citizen of the United States, residing at Preston, in the county of Lancaster, England, have invented a certain new and useful Improvement in Motor-Starting Switches, of which the following is a full, clear, and exact description, reference being had to the accompanying drawings.

One of the objects of this invention is to provide in a simple form an efficient motor-starting switch which may be operated by a single handle both to close the circuit primarily and to cut out the resistance and which will automatically release itself if left at an intermediate position.

Other objects are to provide a simple and efficient blow-out for the spark and releasing devices for overload and no load.

The particular embodiment shown in the drawings, which has been found very efficient in practice, is also comprehended in my invention.

The invention may be summarized as consisting of the combinations of parts hereinabove described, and definitely set out in the claims.

Referring to the drawings illustrating my invention, Figure 1 is a front elevation of my motor-starter at the off position. Fig. 2 is a similar view of the same after the crank has been moved to primarily close the switch. Fig. 3 is a front elevation of the main portion of such switch in the final position. Fig. 4 is a diagram illustrating the circuits. Fig. 5 is a plan of the overload releasing-armature, being sectioned through the support for such device. Fig. 6 is a vertical section through the starting-switch and its support. Fig. 7 is a section through the blow-out coil parallel with Figs. 1, 2, and 3. Fig. 8 is a bottom view of the blow-out coil as indicated by the line 8-8 of Fig. 7. Fig. 9 is a substantially central vertical section of the blow-out coil as indicated by line 9-9 of Fig. 7.

Referring to the drawings by reference characters, 10 represents the support for the structure, which may be a piece of slate or other insulating material. Extending forward from this support is a stud 11. Journaled on this stud is the member or sector 12, which has teeth 13 on its periphery adapted to be engaged by a tooth 14 on the shaft of the operating-crank 15. The sector 12 carries a contact-brush 16, adapted to engage the various individual contacts 18. The brush

also has a portion 29 adapted to engage the arcual bar 17, connecting it with a contact 18. The rotation of the crank-handle 20 swings the sector 12 on its pivot to cause the brush 16 to travel from one contact 18 to another. The teeth 13 are concave on their ends to engage the shank of the crank, whereby the sector is held in place, while the notches between the teeth are adapted to receive the single pinion 14, whereby the sector is advanced one tooth for each rotation of the handle, such movement causing the brush 16 to pass from one contact 18 to another. The sector 12 is forked at the pivot, having its front plate journaled on the pivot-pin near its outer edge and having an ear 22 journaled on the pin adjacent to its support, this ear being carried by a curved wall 23, which is connected by webs 24 with the body of the member. Between the plate 21 and the ear 22 is journaled the lower end of the arm 30, which carries the contact-brush 31 and the contact-finger 32, the latter of which is pivoted to ears 33, carried by the arm, and is pressed toward the brush by a spring 34, secured to the arm and bearing against the lower end of the finger. This arm 30 is likewise forked at its lower end, as shown in Fig. 6, and within the fork is located a flat spiral spring 35, the inner end of which is connected to the pin 11, seating in a groove therein, the outer end bearing against the curved wall 38 of the arm, as shown in Fig. 3. The effect of this spring is to give the arm 30 a tendency to withdraw the brush 31 and contact-finger 32 from the main contact-plate 50, hereinafter referred to, thereby breaking the circuit at that point.

Journaled on the stud 11 between the forward fork 39 of the arm 30 and the front plate of the sector 12 is an arm 40, which extends behind the sector 12 and is allowed a limited movement independently thereof. A lug 41 on this arm extending between two webs on the rear side of the sector 12 limits the independent movement of the arm. A spring 42, carried by the arm, bears at one end against a web 43 of the arm and at the other end against a lug 44, depending from the hub of the arm 40. From the inner face of the hub of the arm 40 extends a pin 45, occupying an arcual slot 46 in the ear 39 of the arm 30.

With the parts in their "off" position (shown in Fig. 1) the spring 42 holds the arm 40 with the lug 41 against the uppermost web of the member 12, and this causes the

pin 45 to take a position where the arm 30 may be held by means of the spring 35 in its off position—that is, with the contact portion away from the main contact 50 and the arm against the stop 48. If the crank be given a partial rotation in the left-hand direction, the hook-shaped arm 49, carried by the shank thereof, engages the upper edge of the arm 40, swinging it downward against the action of the spring 42, and this movement, by reason of the pin 45 bearing against the end of the slot 46, swings the arm 30 upward to cause the brush 31 and finger 32 to contact with the main contact 50, closing the circuit through the resistance to the motor. When the main circuit is closed by the left movement of the crank into the position shown in Fig. 2, a releasing-magnet 60 becomes energized, and its pole-pieces 61, operating with an armature 62, hold the arm 30 in closed position, as shown in Figs. 2 and 3. The armature 60 is adjustable by reason of studs extending therefrom loosely into recesses in a boss 64 in the arm, a set-screw 65 engaging one of such studs to hold the armature in adjusted position.

The circuits will be hereinafter explained in connection with the diagram. For the present it is sufficient to say that each of the contacts 18 is a terminal of a line leading from the resistance, the resistance decreasing with successive contacts from left to right. In the first active position the current flows from the contact member 50 through the brush and arm 30 and the member 12 and brush 16 to the contacts and through the entire resistance to the motor. A pig-tail 47 is provided, making a good electric connection between the arm 30 and the sector 12. If the crank 15 after closing the circuit be rotated in the right-hand direction, the sector 12 is advanced one tooth for each rotation, successively cutting out the resistance until in the final position (shown in Fig. 3) the resistance is entirely cut out. During the first rotation of the crank the swinging of the sector raises the arm 40 out of the way of the hooked arm 49, and during consecutive rotations the arm 40 swings upward with the sector, the arms thus occupying idle positions except in starting.

The blow-out device is covered by my Patent No. 691,693, granted to me January 21, 1902. As shown in the present case, however, it possesses certain novel characteristics claimed herein. It comprises an iron core 51, having a flange 52 and a stud 72, by which it is bolted to the support 10 and connected with one of the main lines. On this core between a pair of insulating-plates 53 and 54 thereon is a winding comprising a flat copper ribbon 55 and an intermediate strip of insulation 56. The ribbon is secured to the core by a rivet 57 and with its insulation is wound spirally around the core, as indicated in the

drawings. The intermediate turns of the spiral are omitted in Figs. 1, 2, 3, and 7 for ease of illustration. The final turn of the ribbon is secured to a brass block 58 by screws 59. This block is of the triangular shape shown, being curved on its upper face to fit the spiral and having inclined lower faces to receive the end of the ribbon 55 and the main terminal plate 50, fastened by screws on the other face. The block 58 is held in place by a screw 66 passing through the support 10 and insulated from the flange 52. An iron plate 67 is placed on the outer side of the insulating-plate 54 and is secured to the core by a screw 68.

It will be seen from the above description that I have provided a magnetic blow-out with an exposed metallic shield which operates to stretch the spark around the blowout itself, as explained in my patent referred to. In the present instance, however, the last turn of the copper ribbon itself forms the shield. This is a simple construction, dispensing with the necessity of an additional shield, and is very effective in practice. It is to be understood that a sufficient space is provided around the shield for the passage of the spark. As shown in the drawings, there are a pair of inclined wooden strips 69 which are held between the two insulating-plates 53 and 54 near their edges, whereby an insulating box is provided for the blow-out. This box is entirely open above and the spark in tending the arc around the blow-out may pass freely out of the top of the box. Use the blow-out device also as a magnet for preventing overload. To this end the flange 52 of the core and the front plate 67 have downwardly-extending lugs 70 and 71, respectively, forming pole-pieces. Beneath these pole-pieces is the armature 73, carried on a lever 74, pivoted in a bracket 75, carried by the support 10. The lever 74 extends rearwardly from its pivot, as shown at 76, and this rearward portion extends over a spring-terminal 77, which is normally out of engagement with a terminal pin 78 beneath it. A set-screw 79 adjusts the normal position of the lever 74.

The lever 74 is normally idle, but in case of an overload the increased magnetism of the pole-pieces 70 and 71 raises the armature 73, causing the tail 76 to depress the spring 77 into engagement with the terminal 78. This, as is hereinabove explained in connection with the diagram, short-circuits the release-coil 60, which releases the arm 30, allowing it to move to the left under the action of its spring 35, thereby breaking the contact between the brush 31 and finger 32 and the terminal plate 50. As this contact is broken the arc flies upward into the insulating-box around the metallic shield 55, and is blown out thereby.

The contact-brush 31 is a laminated structure, and to prevent this being unduly burned

by the arc I provide the finger 32 referred to, which is pivoted to the arm 30 and acted on by the spring 34. When the arm swings away from the terminal plate 50, the spring 34 keeps the finger 32 in engagement with this plate until after the brush has cleared the plate, so that the arc is between the end of the finger 32 and the plate 50. The end of this finger 32 as well as the plate 50, are 10 easily removable and may be replaced when unduly burned.

As is heretofore explained, it is the magnetism of the magnet 60 which holds the brush 31 in engagement with the terminal 50 after the circuit has been closed. Circuits are provided which normally short-circuit the magnet 60 in all positions of the sector 12, except the final position. A push-button 80 is provided, which when pressed is adapted 20 to open this short circuit. When the switch is being turned on, the operator must keep his finger on the push-button 80 to allow the magnet 60 to be effective to hold the arm 30 in closed position. If he releases the push-button before the final position is reached, the short-circuited magnet releases the arm 30. In the final position the short circuit is broken and the pressure may be removed from the push-button. By this provision it is impossible 30 for the operator to go away accidentally and leave the switch standing on an intermediate position. He must remain at the switchboard until he has brought the switch into the final position.

35 Figs. 1 and 2 show binding-posts 81 and 82 for the armature-line and shunt-field line of the motor and a binding-post 83 for one of the main lines, the other main line being connected with the field and armature of the 40 motor. This, as well as the other circuits, are shown in the diagram Fig. 4, to which reference will now be made. The main line B is connected with the binding-post 83. From thence a conductor C leads to the 45 blow-out coil 55 and to the terminal plate 50. From this plate the circuit may continue via the brush-arm 30 and the sector 16 to any of the contact-plates 18 and through the corresponding portion of the resistance 50 R to the line D, which leads to the binding-post 81. From this binding-post the line E leads to the armature A of the motor. From the brush-arm 30 the shunt-line leads through the coil 60 and via the line H to the 55 binding-post 82 and via the line I through the field F of the motor, the field and armature being jointly connected to the return-line J. The releasing-coil 60 is normally short-circuited by the push-button 80, whose 60 contact is connected with the line H and by a line K with the contact 17. In starting the motor the operator presses in the button 80, opening the short-circuit line around the release-coil 60. He then swings the crank 15 in the left-hand direction, the hook 49 engag-

ing the arm 40 and swinging the arm 30 and bringing the contact-finger and brush into engagement with the contact-plate 50. This causes the current to flow through the entire resistance and the armature of the motor and the shunt-current to flow through the release-coil and the field. Now the rotation of the crank 15 in the right-hand direction gradually moves the arm 16 to the right, so that it passes to successive buttons 18, cutting 75 out successive sections of the resistance R, one section being cut out for each rotation of the crank. If the operator should accidentally go away from the switchboard with the arm 16 in any intermediate position, the operator's release of the push-button 80 would cause the release-coil 60 to be short-circuited via the line 16, bar 17, the line K, the push-button, and the line H. This would release the arm 30, which would fly back, breaking 85 the circuit between the contact-finger carried by the arm 30 and the contact-plate 50. This leaves the sector 12 in whatever position it occupied; but before the arm 30 can be moved to closed position the sector must be 90 rotated back to its first position to bring the arm 40 into position for engagement by the hook 49. Assuming that the operator continues his pressure on the push-button 80, the arm 16 is caused to successively travel 95 from one button 18 to the next until it finally reaches the last button, cutting out the entire resistance. The bar 17 terminates at the next to the last position, and in the last position the portion 29 of the brush 16 which 100 was engaging the bar 17 leaves it and comes onto the idle button 19. This breaks the short circuit through the push-button irrespective of the position of the push-button, and the operator may leave the switch in its 105 final position. If an excessive current comes on the main line, this gives sufficient magnetism to the pole-pieces 70 and 71 to cause them to draw up the armature 73, closing the contacts 77 and 78. This forms a short circuit around the releasing-coil 60 via the line L, thus releasing the arm 30, and the spring 35 withdraws the arm, breaking the contact. If for any reason the current on the 110 main line should cease, the release-coil 60 loses its magnetism and releases the arm 30, breaking the contact. In either case the sector must be rotated back to initial position before the motor can again be started.

I claim—

1. In a motor-starting switch, the combination with terminals, one of which is movable, an operating member, and means whereby one movement of said member may cut out resistance, and another movement of said member may bring the terminals together without altering the position of the resistance-governing mechanism.

2. In a motor-starting switch, the combination of a pair of terminals, a spring tending 120

to separate the terminals, a magnet adapted to hold the terminals together, a crank, and mechanism whereby movement of the crank in one direction cuts out resistance, and movement in the opposite direction closes the terminals without displacing the resistance-governing mechanism.

3. In a motor-starting switch, the combination of a crank, a member connected thereto with and adapted to be moved by rotation of the crank, means for cutting out resistance controlled by said member, mechanism for primarily closing the circuit, said mechanism being adapted to be operated by movement of said crank, without disturbing said member, and a magnet for maintaining the circuit normally closed.

4. In a motor-starting switch, the combination of a terminal, a movable terminal member adapted to coöperate therewith, an armature carried by said movable terminal member, a magnet coöoperating with said armature, a spring tending to separate the terminals and move the armature away from the magnet, a crank, and mechanism whereby by movement of the crank in one direction cuts out resistance and movement in the opposite direction closes the terminals without displacing the resistance-varying mechanism.

3c. 5. In a motor-starting switch, the combination of a terminal, a pivoted arm carrying a terminal member adapted to coöperate with the terminal first mentioned, a spring tending to move said arm into position to break contact between the terminals, a magnet adapted to hold said arm with the terminals in engagement, an operating member, means whereby movement thereof in one direction operates to move the arm to close the terminals while the resistance-governing member is stationary, and such resistance-governing member operated by the movement of said member step by step in the other direction.

45. 6. In a motor-starting switch, the combination of a support, a stud mounted thereon, a circuit-closing arm having a fork mounted on said stud, a spring occupying said fork and coiled around the stud and secured at one end to it and the other to the arm and adapted to move the arm into position to open the circuit, a manually-operated device adapted to swing the arm to close the circuit, a resistance-governing member journaled on said stud and connected with said manually-operated device to be moved thereby.

7. In a motor-starting switch, the combination of a circuit-closing arm, a member carrying a movable contact to cut out resistance, a second member movable with the member mentioned but having some movement independently thereof, which latter movement is adapted to move said arm to close the circuit, and a manually-operated

device adapted to move the members mentioned independently. 65

8. In a motor-starting switch, the combination of a circuit-closing arm, an operating-crank, a member geared with said crank and carrying a movable contact to cut out resistance, and mechanism movable with said member but having some movement independent thereof, which latter movement is adapted to move said arm to close the circuit. 75

9. In a motor-starting switch, the combination of a member, an arm having a spring connection therewith, means for operating said arm to close the circuit, and means for giving said member a partial rotation to cut out resistance, such movement of the member carrying said arm to an idle position.

10. In a motor-starting switch, the combination of a circuit-closing arm, another arm having a loose-play connection with the circuit-closing arm and a spring connection with a sector, means for operating the last-mentioned arm to close the circuit, and for operating said sector to cut out resistance, said movement of the sector carrying said arm out of the way of said means. 85

11. In a motor-starting switch, the combination of a support, a stud carried thereby, a circuit-closing member journaled on said stud, a sector journaled on said stud, an arm journaled on said stud and having a loose-play connection with the circuit-closing member and a spring connection with the sector, means for operating said arm to close the circuit and for operating said sector to cut out resistance, said movement of the sector carrying said arm to an idle position. 95

12. In a motor-starting switch, the combination of a support, a stud mounted thereon, a circuit-closing arm mounted on said stud, a spring surrounding the stud and secured at one end to it and at the other to the arm, and adapted to move the arm into position to open the circuit, a magnet tending to hold said arm in position with the circuit closed, a manually-operated device adapted by one movement to swing the arm to close the circuit, and by another movement thereof to cut out resistance. 105

13. In a motor-starting switch, the combination with contacts engageable and separable, of a blow-out device placed within the sweep of the arc, and comprising a spirally-wound ribbon of metal, the last turn of which is exposed to the action of the spark. 115

14. The combination with engageable and separable contacts, of a blow-out device therefor comprising a spirally-wound ribbon of non-magnetic metal, the turns having its exterior exposed to the action of the spark. 120

15. The combination with a magnetic core of a ribbon of conductive non-magnetic material secured at one end to the core and 125

spirally wound around it with insulation between successive turns, the last turn forming an exposed metallic shield for the winding, a terminal block with which the end of said ribbon is connected, and a coöperating movable terminal adapted to form electric connection with said block.

16. The combination with a stationary terminal and a movable pivoted arm adapted to engage the terminal, of a blow-out device located above such contacts and comprising a coil with an exposed metallic shield in an insulating-box having a space around the shield and open above the shield.

17. The combination with a support, of a metallic core carried thereby, a pair of insu-

lating-plates mounted on the core, a ribbon of metallic non-magnetic material secured to the core and wound spirally around the same with interposed insulation between the turns, a terminal block connected with the outside winding of the coil, and insulating-pieces between the two insulating-plates at their edges to form a box around the coil, said box being open above and leaving space around the coil.

In testimony whereof I hereunto affix my signature in the presence of two witnesses.
